UNITED STATES PATENT OFFICE.

JOHN MARTINO, OF PHILADELPHIA, PENNSYLVANIA, ASSIGNOR TO STOUT
& MAREMBECK, OF SAME PLACE.

DESIGN FOR RANGE.

Specification forming part of Design No. 7,519, dated June 30, 1874; application filed June 15, 1874.
[Term of Patent 7 years.]

To all whom it may concern:

Be it known that I, JOHN MARTINO, of the city and county of Philadelphia and State of Pennsylvania, have invented or produced a Design for Cooking-Range, of which the following is a specification:

The nature of my design is fully represented in the accompanying photographic illustrations, to which reference is made.

The fire-box A has on its base a projection, the lower edge of which is ornamented by a small urn-like ornament, alternated by a spear-shaped leaf, they being tied together at their lower edges. This base and projection also run across the oven-front, and are ornamented in the same manner.

The fire-box A has on either side an oblong panel, 1, running from bottom to top, with a small double-pointed spear-shaped ornament in its center.

Immediately above and below this ornament, and within said panel, are small panels scored diagonally.

From the projection of the upper rail, 2, and immediately above the upper doors, A, are small leaf-shaped ornaments running across, pointing downward.

The oven-front B has a chain-shaped ornament, the spaces between the strands of the chain being depressed to form a panel, the ground of which is scored diagonally.

4 is a center ornament or panel, raised in the center, of cushion shape, having on its

face a dotted Maltese cross, with a star in its center, and said panel has on its periphery leaf-shaped projections.

The doors A of the fire-box are ornamented in the same manner as those on the oven-front B. In the center of the doors A are registers, through which the air passes, the blanks of the registers through which the air passes being ornamented with a leaf.

5 is an oblong panel above the lower door, having on either end a leaf pointing inward.

6 is a long ornamental strip, divided into two parts. The center ornaments in each part are the same as on panel 1, and they are scored diagonally.

The end C is ornamented by being formed in the shape of a panel, with an ogee bead, the said panel in each of its four corners having a spear-shaped ornament, with two projecting hooks or scroll-shaped leaves on either side. The center ornament of this panel has a dotted Maltese cross in its center on a flat panel, the said flat panel being diagonally scored, and the outer part of this panel is similar to 4.

What I claim as my invention is—

A design for a cooking-range, substantially as described above.
